[57] CLAIM

The ornamental design for an endotracheal intubation kit tray, or the like, substantially as shown and described.

DESCRIPTION

FIG. 1 is a top plan view of an endotracheal intubation kit tray, showing my new design;

FIG. 2 is a side elevation thereof;

FIG. 3 is a front elevation thereof;

FIG. 4 is a bottom view thereof;

FIG. 5 is a sectional view thereof taken at 5—5 of FIG. 1;

FIG. 6 is a sectional view thereof taken at 6—6 of FIG. 1.

FIG. 1

FIG. 2

FIG. 3

FIG. 4

FIG. 5

FIG. 6
